UNITED STATES PATENT OFFICE.

WILLIAM I. BROWN, OF TOLEDO, OHIO, ASSIGNOR TO THE JENNISON-WRIGHT COMPANY, OF TOLEDO, OHIO, A CORPORATION OF OHIO.

FLOORING.

Application filed November 11, 1924. Serial No. 749,149.

This invention relates to sectional or block flooring or surfacing.

This invention has utility when incorporated in wood block flooring wherein the blocks are sealed in their grouping for knitting together into a unit.

Referring to the drawings:

Fig. 1 is a fragmentary perspective view of an embodiment of the invention in an interior flooring;

Fig. 2 is a view similar to Fig. 1 in which the blocks are of a different form than the showing in Fig. 1;

Fig. 3 is a view along the side of an intermediate row of the blocks of Fig. 1 as in a flooring, showing the sealing flow and; Fig. 4 is a perspective view on an enlarged scale, of one of the blocks of Fig. 1.

A structure is shown having doorway 1 from which extends sidewall 2 of a room having subfloor or base 3, over which as a continuous sealing coating is a layer 4. In factory floors or places exposed or subjected to weathering or extremes in temperature or moisture, with the blocks of wood, such sealing coating may advantageously be a resin, pitch, tar or bitumen. As a self setting or hardening coating, after such layer 4 is more or less set but of effective adhering properties, blocks 5 are laid in adjacent or abutting rows thereon, preferably with the joints staggered as between adjacent rows. In such grouping of the blocks 5 on the base 3 to be sealed thereto by the layer 4, the blocks 5 have the grain of the wood thereof on end, or extending away from the base 3.

The blocks 5 have their upper or wear faces 6 expose the age rings of the wood. Grooves 7 extend vertically across the face 40 of longer side 8 of the block 5 away from the wear face 6. Groove 9 parallel to the grooves 7 extends across narrow side or end 10 of the block 5 away from the face 6. Lengthwise of the side 11 as opposite the 45 longer side 8, and parallel with the wear face 6 extends crosswise groove 12. Short side 13 opposite the short side 10, has crosswise of the grain groove 14 extending from the groove 12.

50 As grouped or assembled in the flooring on the base 3, the grooves 12, 14, crosswise of the grain of the blocks 5, extend parallel to the base 3, while the grooves 7, 9, parallel to the grain of the blocks 5 extend away 55 from the base 3. The blocks 5 as preferably

laid, have grooves 7 intersected by grooves 12, and the grooves 9 intersected by the grooves 14. In the completion of the flooring, sealing material 15, as a filler, which is desirably similar to or one which may seal 60 with the coating 4, is poured into the grooves 7, 9, squeegeed over the wear faces 6 for flowing into the grooves 7, 9, or as found convenient introduced to effect sealing knitting between the blocks 5, as well as supplementing the connection of the blocks to the base 3. When this sealing material 15 is a liquid, as pitch, it is desirable to thin such by heating, so it may flow more freely, and still on 65 getting back to the normal temperature to 70 which the flooring is to be exposed, is set or hard. It is, however, desirable not to have such sealing material brittle, but almost plastic.

As the sealing material 15 is flowed into 75 the grooves 7, 9, say as starting along a joint between adjacent rows and taking care of the staggered joints of abutting sides 10, 13, therefrom, the progress of the pouring along the adjacent sides 8, 11, is continuous 80 so that any air entrained by the material 15 as clogging the exposed end of a groove 7, may escape along the vent crosswise grooves 12, 14. This release of support tends to permit the ready flow of the material 15 into 85 the grooves 7, 9. In practice, this material 15 may readily settle below its point of introduction a given distance—say three quarters of an inch. With such ascertained condition as to the action of the material 15, it 90 is desirable to have such distance as a maximum for the spacing of the vent grooves 12, 14, from the base 3. With this proportion maintained, the grooves 12, 14, so vent between the grooves 7, 9, that the pouring or 95 squeegee application of such material 15 is at once, not only down to the grooves 12, 14, but the normal settling distance of the material 15 toward the base 3 beyond these 100 grooves 12, 14. The volume of air below the vents 12, 14, is not such as to sustain the material 15, and once the material 15, even for an attenuated stream portion thereof makes connection with the coating 4, there is surface tension release and effective sealing develops. The quantity of 105 the sealing material 15 which it is possible to introduce between the blocks 5 on a single pouring is thus effective, not only to supply a knitting seal between the blocks as cross- 110

keyed due to the intersecting grooves 7, 9, and 12, 14, but is of such extent that such interconnection between the blocks is maintained even after extended intervals of time 5 and arduous wear, even of vehicle traffic, for the sealing is also of the blocks to the base 3. While initially, the single pouring may not fully charge the grooves, such pouring so nearly approximates such condition 10 that the slight settling in the final complete sealing of the material 15 with the coating 4, leaves the grooves 12, 14, submerged by the material 15 upward therefrom in the grooves 7, 9.

15 Grooves 16, in blocks 5, Fig. 2, are in pairs adjacent intermediate projection 17 as a countersunk lug, but are assembled and coact in the flooring with the sealing material 15 as flowing therealong into and past the 20 crosswise grooves 12, 14. As the projections 17 are beyond the vertical faces of these blocks 5, the material 15 may extend as a more or less thick sheet or film in sealing the vertical faces of the blocks as abutting, 25 thereby being a factor in housing the flooring block or section with an antiseptic or preservative as to all portions thereof not open to direct wear.

While the sealing material 15 may be 30 flowed into its sealing combination, as in such sealing assembly, there is a knitted together unit. As such it has its strength against distortion increased. The interspa-

cial regions are not air pockets, but block side sustaining sealing material. Accordingly the individual blocks are strengthened. Tendencies to warp or curl, even with blocks of greater width than depth, are minimized, if not fully eliminated. While each block is 35 separately supported, the sealing knits such 40 blocks into a homogeneous flooring.

What is claimed and it is desired to secure by Letters Patent is:

A flooring comprising wood blocks of right general parallelopiped form having on 45 two adjacent sides grooves parallel to the grain of the wood of the block, and extending from the wear face of the block, and on the two adjacent remaining sides as extending from said wear face having communicating 50 grooves crosswise of the grain of the wood of the block, said blocks as in rows in the flooring having the crosswise grain grooves intersecting the parallel to the grain grooves of adjacent blocks and accessible solely 55 through the parallel grain grooves, and sealing means for uniting the rows of blocks into a flooring by flowing lengthwise of the parallel to the grain grooves from the wear face of the blocks, with vent relief of such 60 flowing provided by said crosswise grain grooves for flow of sealing means from the parallel grain grooves into said intersecting grain grooves.

In witness whereof I affix my signature.

WILLIAM I. BROWN.
